UNITED STATES PATENT OFFICE.

FOWLER S. FORD, OF LOWER CABOT, VERMONT.

GREENHOUSE.

SPECIFICATION forming part of Letters Patent No. 733,829, dated July 14, 1903.

Application filed April 25, 1903. Serial No. 154,340. (No model.)

To all whom it may concern:

Be it known that I, FOWLER S. FORD, a citizen of the United States, residing at Lower Cabot, in the county of Washington and State 5 of Vermont, have invented new and useful Improvements in Greenhouses, of which the following is a specification.

My invention relates to new and useful improvements in greenhouses; and it relates 10 more especially to sashes of novel construction adapted to be used for the roof of a greenhouse.

The object of the invention is to so construct the sashes that they may be detachably 15 secured to and readily removed from a greenhouse.

With the above and other objects in view the invention consists in providing two sets 20 of sashes of substantially the same proportions. Each sash of one of these sets has laterally-extending flanges which are adapted to project over the sides of the sashes of the other set, and when these sashes are arranged alternately upon a greenhouse a substantially 25 solid and waterproof roof is obtained.

The invention also consists in the further novel construction and combination of parts 30 hereinafter more fully described and claimed, and illustrated in the accompanying drawings, showing the preferred form of my invention, and in which—

Figure 1 is a perspective view of a greenhouse having my improved roof-sashes in position thereon. Fig. 2 is a vertical longitudinal section therethrough. Fig. 3 is a vertical transverse section, and Figs. 4 and 5 are detail views of the two forms of sashes employed.

Referring to the figures by numerals of reference, 1 is a greenhouse of any suitable construction having beams 2, 3, and 4 extending transversely thereof at the front, center, and back, respectively. A weather-board 5 is arranged upon the rear end of the greenhouse 45 and extends over the upper beam 4. The upper ends of sashes are adapted to be inserted between this beam 4 and the weather-board. Two sets of sashes are employed in forming my improved roof. One set is composed of rectangular frames 6, having lights 50 of glass 7 therein, as ordinarily, and provided with laterally-extending flanges 8 upon the

upper surfaces of the sides thereof. These flanges are cut away at their upper ends, so as to permit of the insertion of the adjoining 55 end of the sash between beam 4 and weather-board 5. A cross-strip 9 is fastened to the under surface of the sash at such a point as to rest in rear of the beam 3 when the sash is in position upon the greenhouse. The 60 sashes of the second set employed are each formed of a rectangular frame 10, having a light of glass 11 interposed between side flanges 12. These side flanges are preferably 65 of the same size as the sides of the frames 6, and it is therefore obvious that when the frames are arranged alternately upon the greenhouse the flanges 8 of frame 6 will extend over the adjoining side flanges 12 of the frames 10. In this manner a substantially 70 solid roof is obtained. The frames 10 are provided with transversely-extending strips 13 upon their under surfaces, which are adapted 75 to rest in rear of the cross-beam 3, and these strips, as well as the strips 9, serve to hold these sashes in position with their upper ends between the beam 4 and the weather-board 5. It will of course be understood that opaque material may be substituted for the lights of glass. It will be seen that by providing a roof constructed of sashes such as herein described one or more of said sashes can be readily taken off without necessitating the removal of bolts, screws, nails, or similar securing means.

In the foregoing description I have shown the preferred form of my invention; but I do not limit myself thereto, as I am aware that modifications may be made therein without departing from the spirit or sacrificing any 90 of the advantages thereof, and I therefore reserve the right to make such changes as fairly fall within the scope of my invention.

Having thus described the invention, what is claimed as new is—

1. In a greenhouse, the combination with cross-beams; of sashes mounted thereon, and flanges upon the alternate sashes overlapping the adjoining edges of the other sashes.
2. In a greenhouse, the combination with cross-beams, and a weather-board adjacent to one of said beams; of sashes supported upon the beams and projecting under the weather-board, and laterally-extending flanges upon

the alternate sashes, said flanges extending over the adjoining edges of the sashes.

3. In a greenhouse, the combination with cross-beams, and a weather-board within and 5 adjacent to one of said beams; of sashes supported by the beams and projecting under the weather-board, transverse strips secured to the lower surfaces of the sashes and bearing upon the side of one of the beams, and 10 laterally-extending flanges upon the sides of alternate sashes adapted to overlap the adjacent edges of the sashes.

4. In a greenhouse, the combination with cross-beams, and a weather-strip adjacent to one of said beams; of sashes detachably 15 mounted upon the cross-beams and extending under the weather-board.

In testimony whereof I affix my signature in presence of two witnesses.

FOWLER S. FORD.
